UNITED STATES PATENT OFFICE

FREDERICK A. AFFELBAUM, OF NEW YORK, N. Y.

DISPLAY

Application filed August 29, 1931. Serial No. 560,060.

This invention relates to displays, and more particularly to displays of the continuous or repeating type.

Among the objects which the invention has in view are:—To provide a continuous display utilizing a ribbon of any desired length; to utilize such a ribbon without having to alter the supporting means therefor according to the length of the ribbon employed; to concentrate the actuating mechanism; to provide a mechanism such that the ribbon may be of a considerable length without increasing the size of the entire device; to enable the device to be compact without limitation in the length of the ribbon; to secure simplicity of construction and operation, and to obtain other advantages and results as may be brought out in the following description.

In the drawing:

20 Figure 1 is a perspective of a display in suspended position and embodying my invention;

Figure 2 is a plan with the cover removed;

25 Figure 3 is a sectional view on line 3—3 of Figure 2.

Figure 4 is a perspective of the winding arrangement.

Figure 5 is a sectional view on line 5—5 of Figure 2.

30 Figure 6 is a diagram of the wiring.

In the specific embodiment of the invention illustrated in said drawings, the reference numeral 10 indicates a casing of suitable size and shape to accommodate the parts and with 35 a length and height somewhat in excess of the length and height of the display sign desired to present to public view. As here shown, one longitudinal face of the casing, here referred to as the front of the casing, 40 provides a window or opening 11 the precise size of the part of the display sign desired to be thus exposed, so that the sign may be carried inside the casing and be seen through said window. Preferably the sign is located 45 between the window or opening 11 and a translucent pane or light diffusing element 12 within the casing and offset somewhat from the front wall of the casing. Electric bulbs 13, or other source of light, actuated 50 by a source of power, as the battery 14, indi-

cated in Figure 6, may be utilized within the casing behind the pane 12 for adding to the visibility of the exposed portion of the display sign. The light from the bulbs 13 will be diffused by the translucency of the pane 55 and by offsetting of the pane from the sign, so the sign will be very evenly illuminated thereby.

Within the casing, behind the pane 12, and rotating on axes parallel to each other and parallel to the pane, are a pair of relatively large pulleys 15, 16, here shown in a common plane close to and substantially parallel to the bottom of the casing, and also shown peripherally grooved to receive a belt 17 whereby one pulley, as 16, may be actuated by rotation of the other pulley 15. For convenience in distinguishing these pulleys, the one first mentioned, namely pulley 16, will be referred to as the driven pulley, and the other one 70 will be referred to as the driving pulley 15. The driving pulley 15 is itself actuated in suitable manner, which in the present showing is through the agency of an underlying and axially concentric sprocket wheel 18 attached thereto. This sprocket is driven by a chain 19 extending around an adjacent smaller sprocket 20 in turn driven, by suitable reduction gearing in housing 21, from a motor 22 also within the casing and driven 80 by power, if desired, from the same source 14 from which the bulbs 13 are supplied.

Returning now to a further consideration of the two pulleys, the same are preferably rotatable upon upstanding and fixed posts 85 or axles 23, 24 each of which has an added utility as will presently appear. The driving pulley carries upon its upper side and in rotatable unity therewith, an upstanding drum or spool 25 so as to obtain a positive 90 and equal rotation of the drum with the pulley. This drum constitutes the main driving means or contact with a ribbon 25a, and the ribbon is preferably held in surface contact with the drum by means of a pressure roller 95 26. This pressure roller is shown adjustable by means of a transverse supporting arm 27 above the same rigidly carrying the depending roller axle 28 at one end of the said arm, and itself being carried adjustably in a clip 100

or yoke 29 at the other end portion of the arm. The yoke 29 is positioned upon the drum post 23 and frictionally embraces the same as will be understood. The roller 26 is preferably positioned at that part of the circumference of the drum substantially at which the ribbon leaves the drum in operation, so as to obtain full advantage of tight engagement of the ribbon upon the drum for the full length of contact therebetween.

By preference, the ribbon passes from the drum and roller toward the other pulley 16, that is, to the driven pulley, with the ribbon standing edgewise upon the upper face of the pulley and coiled around the post 24 forming the axle for that pulley. It is by virtue of this coil of the ribbon that I am enabled to employ a ribbon of any desired length without any alteration in the mechanism supporting and operating the ribbon. The ribbon should, however, have at least a slight degree of stiffness or self support, such as obtained by a sized cloth or by use of a cellulose ribbon, so that the coiled part of the ribbon will remain upright upon the pulley and coil and uncoil readily by the relative action imparted by the pulley and by actuation of the ribbon from the driving drum.

Above the body portion of the coil of ribbon on said post 24 is a guide 30 in the nature of a fork, the tines of which stand upwardly parallel to the post and the cross bar of which may be carried directly by the post in which the guide will be rigid with respect to the post. The inner convolution of the coil is deflected upwardly into this guide, thereby enabling the ribbon to be continuous, feeding on to the outside of the coil and withdrawing from the inside of the coil.

Taking full advantage of the interior capacity of the casing, the ribbon may be carried around the inside periphery thereof as indicated. From the guide 30 above described, the ribbon is therefrom shown carried to the rear corner of the casing, passing around a cylindrical member 31 thereat, then extending to the other rear corner to pass around another cylindrical member 32 thereat to direct the ribbon to the nearest front corner where its direction is changed again by another cylindrical member 33 enabling the ribbon to extend across the front and contiguous to the window to another front cylindrical member 34 which again directs the ribbon toward the first mentioned cylindrical member near which is located a final cylindrical member 35 around which the ribbon will pass to direct it to the receiving side of the driving drum 25. The ribbon is preferably tensioned; and as here shown, the tensioning means comprise a roller 36 pressing the ribbon against the first mentioned cylindrical member to which the ribbon passes to the coil. While this roller may be freely rotatable, it is preferable in that instance that the

cooperating cylindrical member 31 resist rotation at least to a slight extent so as to necessitate a positive pull by the ribbon between that member and the next member so that all slack in the ribbon will be in the coiled portion thereof and portions extending from the coil to the tensioning rollers 26 and 36. Attention is directed to the fact that since it is necessary to pass the ribbon leaving the coil above another portion of the ribbon, and that it is preferable to do this without turning the ribbon to a horizontal position, the height of the casing is sufficient to accommodate the double height of ribbon where they cross. The ribbon then slopes from one rear corner to the next and from that corner to the first front corner at which place the ribbon is at the proper level so that it will extend across the front of the casing and the window in proper parallel relation thereto. The excess height of the casing will have an advantage in providing surface area, particularly above and below the window for permanent display of suitable nature.

Access to the interior of the casing is obtained by constituting the top thereof a hinged cover, the hinging 37 being here shown as a "piano" hinge along the upper front corner of the casing. In this connection it is also to be noted that the light bulbs 13 are preferably inserted in sockets 38 each independently carried by a bracket 39 individual thereto depending from the cover. Preferably the brackets are of equal length so all of the lengths will be a single elevation. That elevation is such that a line normal to the pane 12 from the light will be behind the solid portion of the front wall and not the window. Light from the bulbs will therefore be subject to refraction as well as diffusion in passing through the pane to the window. However, as signs of this character are very generally suspended, as by chains 40 at or above the level of the observer's eye, the location of the bulb above the window tends to align the general direction of the light rays from the bulb, through the window to the observer. Having the brackets 39 for the bulbs mounted upon the cover, permits of very ready access to the bulbs by swinging the same out of the casing when it is desired to substitute a new bulb for one that has burned out.

I claim:

1. A display as characterized, comprising a rotatable substantially flat surface, a continuous ribbon having a portion thereof extended for display purposes and having another portion thereof coiled and standing edge-wise on said rotatable surface with the ribbon extending from the coil both at its center and at its periphery to make connection with the said extended portion, whereby actuation of the extended portion and rotation of said surface obtains a progressive

simultaneous winding and unwinding of the coil.

2. A display as characterized, comprising a rotatable substantially flat surface, a continuous ribbon having a portion thereof extended for display purposes and having another portion thereof coiled and standing edge wise on said rotatable surface with the ribbon extending from the coil both at its center and at its periphery to make connection with the said extended portion, whereby actuation of the extended portion and rotation of said surface obtains a progressive simultaneous winding and unwinding of the coil, and means in conjunction with the rotation of said coil to actuate the extended portion of the ribbon.

3. A display as characterized, comprising a rotatable substantially flat surface, a continuous ribbon having a portion thereof extended for display purposes and having another portion thereof coiled and standing edge wise on said rotatable surface with the ribbon extending from the coil both at its center and at its periphery to make connection with the extended portion, whereby actuation of the extended portion and rotation of said surface obtains a progressive simultaneous winding and unwinding of the coil, and a pulley in conjunction with the rotation of said coil to actuate the extended portion of the ribbon.

4. A display as characterized comprising in combination with a casing having a window, a rotatable substantially flat surface, a continuous ribbon having a portion thereof extended for display purposes within said casing and in back of said window, and having another portion thereof coiled and standing edgewise on said rotatable surface with the ribbon extending from the coil both at its center and at its periphery to make connection with the extended portion, whereby actuation of the extended portion and rotation of said surface obtains a progressive simultaneous winding and unwinding of the coil, and means on the outer periphery of the said casing for holding said display in suspended position.
